UNITED STATES PATENT OFFICE.

NIELS GEORG SÖRENSEN, OF STOCKHOLM, SWEDEN.

DOOR-CHECK.

SPECIFICATION forming part of Letters Patent No. 514,511, dated February 13, 1894.

Application filed December 26, 1891. Serial No. 416,190. (No model.)

To all whom it may concern:

Be it known that I, NIELS GEORG SÖRENSEN, a subject of the King of Sweden and Norway, residing at Blasieholmstoog 11, Stockholm, Sweden, have invented certain new and useful Improvements in Devices for Retaining Doors or the Like in their Open Positions; and I do hereby declare that the following is a full, clear, and exact description of the invention, which will enable others skilled in the art to which it appertains to make and use the same.

My invention relates to a catch for a door and particularly to the means for operating said catch.

In the drawings: Figure 1, is an edge view of part of the door partly broken away. Fig. 2, is a detail view of the ordinary bolt and the means for operating the connections to the door catch.

In the drawings A² is the door and A the stationary catch secured to the wall and adapted to engage the pawl A' (pivoted in the door) when the door is opened so as to hold it in its open position. Said pawl A' is operated to release the door by the rod B having its lower end entering a curved slot B^x in the tumbler B² which is in the form of a bell crank lever, the upper arm B³ of which engages the lug B⁴ on the ordinary sliding

bolt B⁵ said bolt being pressed by the spring B⁶. The knob spindle is shown at B⁷. By this arrangement the bell crank tumbler operates the lock when the knob is turned to the right. When turning to the left the bar 35 is pulled downwardly and the pawl catch is operated. This insures the engagement of the catches. When turning to the right the catch is released by a slight additional movement after the lower end of the rod B contacts with the lower end of the slot. 40

I claim—

In combination, the ordinary bolt F of the door lock a door catch and operating rod therefor and the means for operating both 45 the bolt and the rod, consisting of a tumbler B' in the form of a bell crank lever having its vertical arm engaging the bolt and its horizontal arm connected directly to the catch rod, said horizontal arm being slotted to receive said rod, substantially as described. 50

In witness whereof I have hereunto signed my name in the presence of two subscribing witnesses.

NIELS GEORG SÖRENSEN.
